CLOSURE CAP AND METHOD OF MAKING
THE SAMEEric B. Kramer and Edward M. Enkur, Baltimore,
Md., assignors to Crown Cork & Seal Company,
Inc., Baltimore, Md., a corporation of New York

Application February 20, 1933, Serial No. 657,734

4 Claims. (CL 215—44)

This invention relates to closure caps, and to new and improved methods of making the same.

The cap of the present invention is of the type adapted for use with bottles, jars, or other receptacles having external threads or lugs on the necks thereof. More particularly, the cap is of the general class known in the art as lug caps.

Caps of the lug type are well known, and have been made by many different methods, and have embodied a great variety of different constructional details. The present cap, when compared with devices of the prior art, has certain fundamental structural differences, which result in definite advantages, as will be pointed out below.

It is a primary object of the present invention to provide a cap of the lug type, in which the lugs are hidden from view when the cap is in use upon a receptacle. It is a further object of the invention to provide a cap having lugs concealed within the cap skirt and constructed in such manner that no disfiguring indications or marks appear upon the skirt of the cap adjacent their location.

It is a further object of the invention to provide a cap having a skirt provided with interiorly disposed locking lugs which do not impair the uniformity of appearance of the exterior surface of the cap.

It is a further object of the invention to provide a cap of the concealed, internal lug type in which the material of the cap adjacent the lower edge of the skirt is not deformed to a degree sufficient to injure the lacquer coating which is conventionally applied to the cap making material before the same is formed into the completed article.

It is a further object to provide a cap of the type specified, in which no raw edges are exposed so as to be contacted by the hands of a user, or to engage directly a receptacle thread.

It is a further object of the invention to provide a new and improved specific lug structure, characterized by great strength and rigidity, in which a turned edge constitutes a reinforcing member, and serves the additional function of presenting a rounded thread engaging surface.

In the past many attempts have been made to design and manufacture a commercially satisfactory lug cap having a smooth exterior surface, and provided with inwardly projecting locking lugs which are concealed when the cap is on the receptacle, and the location of which is not indicated by indentations or other disfiguring marks on the exterior of the cap skirt. All of these attempts have fallen short of the desired result in one respect or another. In some cases

the lugs were made up of a single thickness of metal, and were defective because of their inherent weakness, or because they presented a raw edge for contact with the receptacle thread. In other cases the lower edge of the cap skirt was necessarily provided with indentations or other deformations at points adjacent the lugs. In still other constructions, it was necessary to provide an outwardly rolled bead on the lower edge of the skirt to hide the lugs, and such bead destroyed the smooth uniform appearance of the cap. Certain prior art constructions, in which the lower edge of the cap skirt was turned inwardly and upwardly and pressed into a flat fold or hem in contact with the inner face of the skirt and merging with the bottom of the skirt in a sharp fold line or crease, have been found defective because the lacquer coating on the cap making metal cracks and chips off along the sharp fold or crease, with a consequent ruinous effect upon the appearance of the completed cap.

By the construction embodied in the cap of the present invention, all of the defects of prior art caps of this general type are avoided, and all of the objects of the invention accomplished.

The cap of the present invention comprises a skirt having its lower edge rolled inwardly to form an interiorly disposed, circumferential bead, the cross-sectional curve of which is, at no point, sharp enough to injure the lacquer coating on the cap making material. The cross-sectional curve which marks the juncture between the lower part of the cap skirt and the inwardly rolled bead is constant around the entire circumference of the skirt, and consequently, the lower edge of the skirt presents a uniformly rounded surface, entirely devoid of indentations or other deformed spots.

The inner surface of the inwardly rolled bead is provided at spaced points with inwardly projecting, reinforced, rounded locking lugs. The lugs may be formed with various different specific structures, and several alternative methods of making them may be used. It should be distinctly understood, therefore, that the accompanying drawings, showing two preferred forms of cap and one method of making a cap, are illustrative only, and that the invention is in no sense limited to the details thereof.

In the drawings:

Figure 1 is a vertical axial sectional view of a cup-shaped blank from which the cap of the present invention may be made;

Figure 2 is a similar view showing the blank

- after a preliminary step in the method has been completed;
- 5 Figure 3 is a similar view showing the blank after the first bead forming operation has been performed on the edge of the skirt;
- 10 Figure 4 is a similar view of the blank after the first lug forming step has been completed;
- 15 Figure 5 is a similar view showing one form of completed cap;
- 15 Figure 6 is a bottom plan view of the cap of Figure 5;
- 20 Figure 7 is an elevational view of the cap of the present invention, showing the smooth exterior surface of the same;
- 25 Figure 8 is a bottom plan view of a similar cap, showing a somewhat modified form of lug;
- 25 Figure 9 is a vertical axial section of the cap shown in Figure 8, taken through the lugs;
- 30 Figure 10 is a top plan view, with a portion broken away to expose the modified form of lug;
- 35 Figure 11 is an enlarged vertical sectional view of one edge of the cap skirt, corresponding to the step shown in Figure 2;
- 40 Figure 12 is a similar view corresponding to Figure 3;
- 45 Figure 13 is an enlarged vertical sectional view through the circular bead portion after the step represented by Figure 4 has been completed;
- 50 Figure 14 is a view similar to Figure 10 but taken on a section through one of the lugs;
- 55 Figure 15 is an enlarged vertical sectional view taken through the bead portion of the completed cap;
- 60 Figure 16 is a similar view, taken through one of the lugs;
- 65 Figure 17 is an enlarged sectional view of the completed cap on a receptacle, showing the manner in which the lug engages a receptacle thread;
- 70 Figure 18 is an enlarged top plan view, partly in section, showing a specific lug structure;
- 75 Figure 19 is a vertical sectional view of an apparatus which may conveniently be employed for performing the step in the method represented by Figure 2;
- 80 Figure 20 is a similar view, with certain parts omitted, showing the first curling die;
- 85 Figure 21 is a similar sectional view of the apparatus taken on line 21-21 of Figure 22, and shows the die which performs the preliminary lug forming step;
- 90 Figure 22 is a bottom plan view of the die disclosed in Figure 21;
- 95 Figure 23 is another vertical sectional view of the apparatus disclosed in Figure 21 but taken on section 23-23 of Figure 22; and
- 100 Figure 24 is a vertical sectional view through the apparatus showing the die which performs the final step in the method, and completes the several cap forming operations.
- Two specific embodiments of the completed cap of this invention are disclosed in Figures 5 to 10 and 15 to 18. The cap comprises a top 25, which may be either flat as disclosed in several figures or of substantially dome-shape as disclosed in Figures 19 to 24, or otherwise formed. A downwardly depending substantially cylindrical skirt 26 preferably has a smooth exterior surface and merges with the top in a rounded corner, but, of course, any appropriate decorative embossing may be applied to the skirt if desired.
- 75 The skirt is provided around its entire circumference with a uniformly inwardly turned lower edge 27, the cross-sectional curve of which is constant around the circumference of the cap, to present a uniform appearance. The material of the cap interiorly of the rounded edge 27 continues inwardly and upwardly in a roll or bead 28. This bead is substantially circular in cross-section at all points around the circumference of the skirt except at certain spaced points where the lugs are situated. The bead at the latter points is uncured, or rolled up to a lesser degree, so that it extends radially inwardly further than the adjacent bead portions to provide locking lugs.
- In Figures 15 and 18 the substantially circular, inwardly turned bead portions 28 are disclosed in section. It will be noted that the cross-sectional curve at the lower edge of the cap skirt, between the cylindrical portion thereof and a circumferentially extending line therebelow, such as the locus of all lowermost points 29 on the bead, is constant on all axial sections. This curve is continued on substantially the same radius inwardly from that line to form an inwardly disposed substantially circular closed head along arcuate sections of skirt circumference. In Figures 16, 17 and 18, which show the lug in cross-section, it will be seen that although the outer curve between the skirt and the line of the points 29 is the same as at the bead portions, the cross-sectional shape of the inwardly extending roll 30 is different, is somewhat flattened, or is struck on a circle of large radius. As a result, the end portion of the skirt at these places extends inwardly beyond the adjacent closed bead portions and forms locking lugs 31. Preferably the edge of each of the lugs is turned outwardly, as at 32, to provide a concealed edge, to function as a reinforce for the lug, and to present a rounded thread engaging surface 33.
- The lug of the present invention has a thread engaging surface which, as stated above, is rounded cross-sectionally as disclosed in Figures 5, 9, 16 and 17. The thread engaging surface is also rounded in a direction circumferentially of the cap, as shown in Figures 6, 8, 10 and 18.
- It will thus be seen that the skirt of the cap of the present invention is turned inwardly throughout its entire circumference to form a concealed edge, which edge is curled or rolled upwardly to provide a continuous bead, and that the bead at spaced points is uncured, or rolled up to a lesser degree to provide inwardly extending locking lugs. Whereas the head is circular in cross-section and substantially closed along the arcuate sections 28, it is open and extended inwardly at spaced portions 31 to form locking lugs. At the open portion, the edge is turned outwardly at 32, in order to reinforce the lugs and also to provide a rounded thread contacting surface.
- It will also be noted that the lugs are horizontally aligned with the intermediate bead sections. The bottom of each of the uncured portions is aligned with the closed bead portions so that the cap presents a smooth lower edge, and the tops 33 of all of the lugs are substantially in alignment with the upper surface of the bead portions.
- Where in the claims the cross-sectional shape of the roll at the lugs is referred to as being curved on a larger radius, we mean any shape, including substantially flat, which is less sharply curved than the roll 30.

curved than the external curve at the lower edge of the cap skirt.

The lugs have been described as portions of the rolled end of the skirt, or bead, which are uncurled, or rolled up to a lesser degree than the adjacent portions, and these terms must be understood to relate to structure, and not to the method of manufacture, as the lugs might be made by curling the entire bead and subsequently uncurling, or unrolling portions thereof. On the other hand, they may be formed by simply refraining from curling certain portions of the bead as much as other portions are curled. Also, the lugs might conceivably be formed by axially flattening and radially extending certain portions of the bead by applying force to the top of the bead, with the bottom supported upon an anvil having a forming groove with a cross-sectional curve corresponding to the desired uniform curve to be imparted to the exterior of the lower edge of the cap.

In Figures 8, 9 and 10, a cap having a somewhat modified form of lug is shown. This type of lug may conveniently be formed by a method similar to the method described in this application, but differing therefrom in certain respects, as is clearly pointed out in the co-pending application of Edward M. Enkur, Serial No. 660,927, filed March 15, 1933. The essential difference in the method resides in an additional step, between the steps disclosed by Figures 3 and 4, which comprises bending outwardly on predetermined arcuate curves, spaced portions of the partially formed bead or wire. Such outwardly bent portions are then swung inwardly during the course of the step shown at Figure 4.

A comparison between Figures 6 and 8 reveals that the essential difference between the two specific forms of lugs is that the one shown in the latter figure is considerably shorter, circumferentially of the cap, than the first form, but has substantially the same radial depth. The arcuate curve 31a of the innermost edge of the lug 31' is struck on a radius which is a great deal shorter than the radius of the arc upon which the inner edge of the lug 31 is struck. Since the radial projection of the two lugs is the same, it follows that the number of degrees on the arc of lug 31' is greater than on lug 31.

Certain advantages follow in certain cases from having the lug relatively short and deep, as opposed to long and shallow as in the form of Figure 6. It is within the scope of the present invention to make the lug of any desired form and shape, depending upon the particular use to which the cap is to be subjected.

A comparison between the several figures discloses that, although the lugs of the modified form have a materially different shape in plan, they are substantially identical to the first form in section.

A preferred method of making the cap of the present invention is disclosed in the drawings, and will now be described. A cup shaped blank having a top 25 and a cylindrical flange 26 is made in a conventional drawing operation from a sheet of metal usually having a lacquer coating on its lower surface, or, in some cases, on both surfaces. In the several forming operations which convert the shell disclosed in Figure 1 into the completed cap of Figure 5, the blank is preferably positioned upside down, as shown, and is moved step by step from one press to the next. The general plan of the machine forms no part of the invention of the present application,

and consequently the specific means for simultaneously moving a plurality of blanks in a step-by-step motion to the various stations is not disclosed.

The blank of Figure 1 has a substantially cylindrical skirt 26, terminating in a raw edge 35, which normally is slightly outwardly flared when the blank comes from the drawing dies. Since in the present method it is necessary to curl the end portion of the skirt inwardly, it has been found expedient to first start the curl by turning the free edge from its outwardly flared position to a slightly inwardly bent position. This first step in some cases may be dispensed with, but it has been found desirable with the usual run of blanks. The result of the preliminary edge bending operation is disclosed in Figures 2 and 11, and it will be noted that the cross-sectional shape of the skirt edge has been changed just enough to facilitate the next curling operation.

The second step in the method comprises giving the edge of the cylindrical flange a substantially semi-circular, inwardly disposed curl, as disclosed in Figures 3 and 12. This step may be performed by a die, such as is disclosed in Figure 20, to be described below.

The third and most important step in the method comprises continuing and substantially closing the already partially formed roll or bead entirely around the circumference of the cap skirt, except at certain spaced points, where the roll is not continued but is left open and is merely bent radially inwardly to form radial enlargements, which are subsequently shaped into locking lugs. The blank after this step has been performed is disclosed in Figures 4, 13, and 14, and the die which performs the step is disclosed in Figures 21, 22 and 23, and will be described below. The lug forming projections 37 have their outer surfaces 38 disposed on an inclined plane, and extend axially outwardly beyond the adjacent curled portions 28. Since the rolled edge 36 of Figure 3 was not curled up at the lug portions, the edge 36 extends radially inwardly a substantial distance.

The final step in the method comprises bending the incipient lugs 37 into the interior of the cap shell, causing the several surfaces of the lugs to assume a predetermined position, and imparting a slight additional roll to the intermediate bead portions 28. After this step has been completed the cap is finished and the bead portions are in the form of substantially closed tubular sections, as disclosed in Figure 15, and the lugs are relatively uncurled, or less curled, as disclosed in Figures 16 to 18 inclusive.

Figures 19 to 24 show various forms of dies and associated apparatus parts adapted to perform the steps enumerated above.

In the apparatus of Figure 19, a stationary base block 50 is provided with a socket in which is mounted a nest 51, supported by a spring-pressed plunger 52. Above the block, a die forming assembly is hung from a cross-head 54. This assembly comprises a cylindrical die 55 fixedly secured to the cross-head and having a forming groove 56 on its bottom face. Within a central bore in the die 55 is a rod 57 normally projected downwardly by compression spring 58. Upon the lower end of the rod is a clamping pad 59 which, as the parts descend, first comes in contact with the interior surface of the top 25 of the cap blank, to hold the blank in position. Surrounding the rod 57, in spaced relation thereto, and within the die member 55, is a depending sleeve 60 having

its lower end provided with a rounded cam surface 61. Surrounding the sleeve 60, and also within the die 55, is an expanding collet 62 made up of a plurality of spring fingers integral with a ring 63. Each of the fingers adjacent its lower end is provided with an inner cam surface 64 positioned to be engaged by the surface 61 of sleeve 60. Each finger terminates at its lower end in an outwardly projecting head 65. A compression spring 66 is disposed between a shoulder on fingers 62 and the ring 63 and a flange on the upper end of sleeve 60 to maintain each head 65 in contact with the upper surface of pad 59.

When the die assembly descends the clamping pad 59 moves inside of the cap blank, and the pad holds the blank upon the nest. Because the spring 53 below the nest is of lighter tension than springs 66 and 58, the continued movement of the pad 59 depresses the nest and blank 20 into the socket in block 50. Further downward movement, after the nest reaches the bottom of the socket, is permitted by the lost motion between rod 57 and cross-head 54, and by compression of the spring 58. Such downward movement results in relative movement between the sleeve 60 and the fingers 62, and a consequent camming action between their cam surfaces. Thus, each finger is spread outwardly and the heads move into position to support the inner 30 wall of the cap skirt. Immediately thereafter, the bottom surface of the die 55 comes into contact with the edge 35 of the blank flange and the groove 56 gives it a slight inward bend or 35 nip. The fingers 62 are useful in assuring that the bend is confined to an area closely adjacent the edge of the flange.

When the cross head 54 is raised, the movement of the parts is substantially the reverse of that described above, and the blank is raised to a level substantially equal to the top of the block 50 from which position it may be moved to the next station.

Instead of using a spring pressed nest 51, as disclosed in Figure 19, a one-piece stationary nest 45 51', disclosed in Figure 24, may be used to advantage. With a two-part assembly such as is disclosed in Figure 19, a minute groove is necessarily present at the juncture between the movable member 51 and the block 50, and this groove 50 results in the formation of a slight rib, or other disfiguring mark, on the exterior of the blank. When a one-piece construction is used, this difficulty is obviated.

As a substitute for the spring pressed blank 55 ejecting means of Figure 19, the nest may be provided with a central bore to which is connected a compressed air pipe 51''. Thus, after the particular operation has been performed, a blast of air may be utilized to eject the blank 60 with entirely satisfactory results.

In Figure 20 the die structure at the next station is disclosed. In this case it is unnecessary to provide the expanding fingers for the inner surface of the flange. Because the curling die 58 65 merely imparts a beading to the metal which has already been started in the right direction. This die 58 has a circular curling groove in its bottom face which has a substantially semi-circular bottom. It functions to inwardly turn the edge 70 of the flange to a substantially semi-circular cross-sectional curve.

In Figures 21, 22 and 23, a die is disclosed which functions to further bead or curl certain portions of the edge of the blank, and to form 75 incipient lugs at other portions. This die per-

forms the important step in the method disclosed in Figures 4, 13 and 14.

The bottom face of the die is provided with four circumferentially aligned grooves 71, each of which terminates at its ends in widened portions 72. The radially inner wall of each groove at the portions 72 is formed into a smooth rounded shoulder 73. The grooves merge, at their ends, into circumferentially spaced cut-away portions 70, the bottom surfaces of which have no positive forming action upon the bead. The intermediate grooves 71 have substantially semi-circular bottoms, as disclosed in Figure 23. A die constructed in substantially this manner operates upon a partially beaded cap shell to complete the 15 bead along spaced sections and form enlargements thereon at other points. When the die descends, the grooves 71 will continue the curling action started by die 58, but since the groove is interrupted at the points 70, this curling action 20 will not be continued around the entire circumference of the skirt. At the cut-outs 70 the bead will not be rolled up or curled further. However, the tendency to curl imparted to the bead by the die sections 71 will be transmitted through the material of the cap skirt to the portions received in the cut-outs 70, with the result that the latter portions will be drawn and will bend radially inwardly, as disclosed in Figure 21. These 25 portions of the edge extend radially inwardly beyond the adjacent bead portions, and form projections in the nature of incipient lugs. They are completed, and bent to final form during 30 the next step of the method, by the die disclosed in Figure 24.

In the apparatus of Figure 24, expanding fingers 62', similar to the corresponding elements shown in Figure 19, are used. In this case the heads 65' project outwardly under the inturned bead and under the inturned incipient lugs and 40 form an anvil surface which limits the inward axial bending imparted by the die 55'' to the lugs. The bottom face of the die is provided with a continuous curling surface 75 having a rounded corner 76. The curve 76 between the 45 outer side wall of the groove and the bottom is uniform around the entire circumference, and imparts a uniformly rounded lower external edge to the cap skirt. Furthermore, it functions to curl the bead of the cap a little more, and bends 50 the incipient lugs downwardly into contact with the members 65'. Thus, the bottom edge of the cap skirt is uniformly rounded, and all points thereon lie in a common plane. The distance 55 between the top of the cap and the thread engaging surface of each lug is accurately determined by the upper surface of heads 65'.

An important feature of the method resides in the fact that it is unnecessary in any of the several steps to position the blank in any particular angular adjustment with respect to the dies. After the second step the blank is of uniform configuration around the entire circumference of the skirt. After the third step incipient lugs have been formed at certain points. 65 The die of the fourth step has a surface of constant cross sectional shape at all points around its circumference, and the angular position of the blank with respect to the die is immaterial, as each point on the surface of the groove is 70 adapted to complete the intermediate bead portions or the lug portions.

The cap of the present invention may be made by several alternative methods. For instance, it is quite feasible to roll an inwardly disposed bead, 75

as disclosed in Figure 15, entirely around the circumference of the skirt, and then unroll certain portions of the bead to form lugs of substantially the form shown in Figure 16. This unrolling action can be accomplished by inserting an expanding die into the blank, expanding a plurality of die surfaces outwardly into contact with the upper surface of the bead, positioning the lower external surface of the bead upon an anvil, and 10 then applying force to the expanded die to uncurl the bead. The anvil should have a supporting surface which conforms closely to the exterior surface of the bead so as to prevent deformation of the lower edge of the cap skirt. The die surfaces could be of any desired conformation and could be given any desired movement, either to flatten or unroll the bead, and the necessary function would be performed in any event, if certain spaced portions of the bead were projected 15 inwardly beyond the adjacent coiled bead portions.

As an alternative method, a particular shape or contour may be given to the lugs by appropriate dies before the lugs are turned inwardly, as 20 disclosed in the aforementioned copending application of Edward M. Enkur, Serial No. 660,927, filed March 15, 1933.

It should be distinctly understood that the present invention is not limited to the details of 25 the cap disclosed herein, nor to the particular method and apparatus described, because many modifications will occur to one skilled in the art after a consideration of the present disclosure. Consequently the invention must be given a scope 30 commensurate with the present contribution to the art, and should be limited only to the methods and articles described in the accompanying claims, and their equivalents.

We claim:

1. A cap of the lug type having a flange and 40 forming a depending skirt, the flange having its edge portion curled inwardly entirely around the lower end of the skirt to form an internal bead, the inwardly turned edge portion of the flange at

circumferentially spaced points being less curled than adjacent curled portions and forming open portions projecting inwardly from the skirt beyond the adjacent curled bead portions to provide lugs, the raw edge of the flange at said lugs 5 being turned to present a rounded thread engaging surface and to provide a lug having a reinforced edge.

2. A cap of the lug type having a flange and 10 forming a depending skirt, the flange having its edge portion curled inwardly entirely around the lower end of the skirt to form a substantially closed internal bead except at circumferentially spaced portions, said portions being relatively uncurled and forming open bead portions projecting 15 inwardly from the skirt a greater distance than the bead thereby providing lugs, the raw edge of the flange at said lugs being turned to provide a lug having a reinforced edge and a 20 rounded thread engaging surface.

3. A closure cap comprising a top, and a downwardly depending uniformly cylindrical skirt terminating in an upwardly turned edge around the entire circumference of the skirt, portions of said inwardly turned edge being rolled upwardly and 25 outwardly toward the inner surface of the skirt to form substantially tubular bead portions, other portions of said inwardly turned edge being rolled a lesser amount and being extended inwardly of 30 said bead portions to form locking lugs.

4. A closure cap comprising a top, a downwardly turned skirt presenting a uniform exterior surface terminating in an inwardly turned, uniformly rounded lower edge, portions of the inwardly turned edge being rolled up into substantially 35 tubular bead portions, and other portions thereof being rolled up a lesser amount and projecting inwardly beyond the adjacent bead portions to form locking lugs for engagement with a receptacle, said lugs terminating in rounded thread-engaging 40 ends.

ERIC B. KRAMER.
EDWARD M. ENKUR.
